UNDERFRAME FOR CARS.

1,420,352.

Specification of Letters Patent. Patented June 20, 1922.

Application filed October 17, 1921. Serial No. 508,139.

To all whom it may concern:

Be it known that I, ROBERT R. WEAVER, a citizen of the United States, residing at Chicago, in the county of Cook and State 5 of Illinois, have invented a new and useful Improvement in Underframes for Cars, of which the following is a specification.

My invention relates, more particularly, to under-frames of cars, formed with a so-called center sill which extends lengthwise 10 of the car and substantially midway between the opposite sides thereof and of the so-called A-type comprising horizontally-spaced side walls having upwardly-converging portions 15 operatively secured together at their upper extremities substantially coincident with the center line of the sill.

The particular type of center sill referred 20 to is more commonly used in railway cars of the drop-bottom type wherein the bottom of the car is formed of a series of plates generally one series at each side of the center line of the car and hingedly supported to the center sill substantially at the center line, the 25 center sill being formed with the upwardly-tapering portions, as stated, for the purpose of rendering the upper surface of the sill, of as narrow a width as possible in order to permit of the hinging of the door-forming 30 plates, as close to the center line of the car as possible and to reduce as much as possible the presentation by the center sill of a surface upon which the material loaded into the car may be retained in the dumping operation.

In the designing of cars having under-frames formed with center sills of the type referred to, and especially drop-bottom cars, a number of conditions are presented. It 40 is not possible to select for different constructions of cars of the type referred to a center sill of a standard depth, as the depth of sill required to be used varies, depending upon the particular design of car. It is 45 also necessary that the lower portion of the sill be made of such strength as to adequately resist the tensile stresses to which it is subjected in use. The provision of the upwardly-tapering side walls of the center 50 sill, which should not extend at less than 45°, greatly weakens the upper compression zone of the sill. Furthermore, it is highly desirable that, regardless of the depth of sill required to be used for any particular

construction, the metal of the sill be so disposed that the neutral axis of the sill shall lie substantially midway between the top and bottom surfaces of the sill in order to cause the sill to present equal strength on both the compression and tension sides. 55

My primary object, generally stated, is to provide a novel and simple construction of under-frame involving a center sill of the type referred to the neutral axis of which will extend substantially midway between 60 the upper and lower surfaces of the sill; to provide for the stiffening of the upper, compression, zone of the beam to the desired extent by the use of structural members which are provided in standard sizes adapting them, when assembled with the other parts of the center sill, to afford at the compression zone of the sill the necessary amount of metal to cause the neutral axis of the sill to extend substantially midway between 65 the top and bottom of the sill, regardless of the particular depth of sill required to be used; another object is to provide adequate reenforcement to overcome the 70 weakness presented by the sill due to its upwardly-tapering side portions; and generally to so improve sills of the type referred to that they will be better adapted for resisting stresses to which they are subjected 75 in use.

Referring to the accompanying drawings: Figure 1 is a broken plan view of one end of a car under-frame embodying my invention, the hingedly-supported plates forming the bottom of the car and the hinges for the 80 same being omitted. Figure 2 is an enlarged section taken at the line 2 on Fig. 1 and viewed in the direction of the arrow. Figure 3 is an enlarged section taken at the line 3 on Fig. 1 and viewed in the direction 85 of the arrow, this view including the door-forming plates, partly broken away, at the point where the section is taken. Figure 4 is an enlarged cross-sectional view of the center sill of the structure of Fig. 1, the 90 section being taken intermediate the cross members of the under-frame. Figure 5 is a view in side elevation of a portion of the center sill, the portion shown being located at one of the cross-members of the under-frame, the parts of the structure shown in this figure, other than the center sill proper, being shown in section, the section being 95 100 105

taken coincident with the center line of the sill. Figure 6 is a broken section taken at the line 6 on Fig. 5 and viewed in the direction of the arrow, showing a spreader element employed at the part of the center sill coincident with the cross-member shown in Fig. 5, and which is typical of the arrangement at each cross-member of the under-frame; and Figure 7, a perspective view of the 10 spreader member referred to.

Referring to the general arrangement shown in Fig. 1, the center sill of the under-frame therein shown is represented generally at 8, and connected with this center sill, to extend transversely thereof and in spaced relation to each other, is a series of cross-frame members, the one of these end members at the end of the car shown in Fig. 1 being represented at 10, a bolster- 20 forming cross-frame member at 11, it being understood that the members 10 and 11 would be duplicated at the other end of the frame, and intermediate cross-frame members at 12. The ends of the cross-members 25 10, 11 and 12 are connected with angle iron side-frame members 13 in accordance with common practice, the side walls (not shown) of the car being secured to the marginal portions of the framework thus 30 provided.

The car shown is of the drop-bottom type, its bottom being formed of two series of plates arranged at opposite sides of the center line of the car and hingedly connected therewith to swing from substantially horizontal carrying position, to downwardly-inclined, dumping position, each series of 35 plates extending lengthwise of the car frame and being located within the spaces provided between the center sill 8, the side members 13, and the various cross-members 10, 11 and 12. The center sill structure shown, which is of box girder form and of the A-type is formed of a pair of metal 40 members 14 which extend lengthwise of the car frame and parallel with each other. Each of the members 14 is formed of a substantially vertical side portion 15 reinforced at its lower edge by an angle iron 16 45 secured against its outer face as by rivets 17, the lower, horizontal, flanges 18 of these angle irons projecting outwardly. Each member 15 is also provided with an upwardly and inwardly-tapering plate portion 19 extending throughout the length of 50 the sill and terminating at its upper edge in a substantially vertically extending plate-like portion 20 likewise extending the full length of the sill. The members 15 are 55 arranged as shown relative to each other to cause their inclined portions 19 to converge upwardly toward the center line of the sill, and their portions 20 to flatwise oppose each other as shown. The center sill also 60 comprises a structural metal beam 21 of I-shape

in cross-section which extends at its web portion 22 between the portions 20 of the members 14, the portions 20 fitting flatwise against this web at opposite sides thereof and being secured thereto as 70 by the rivets represented at 23 which extend through the portions 20 and the web 22, the upper flange 24 of the beam 21 being located in a plane above the upper edges of the portions 20 as shown, the beam 75 21 extending the full length of the sill.

Located within the structure above described of the sill, is a series of spreader elements represented at 25, these spreader elements, which extend transversely of the sill 80 and are located at intervals along the sill, being positioned therein coincident with the various cross-frame members referred to. The spreader elements 25 are preferably of the box-like form shown and are preferably of integral construction, affording a lower member 26 the bottom of which preferably extends flush with the under surfaces of the flanges 18 and the under surface of the portions 15 of the members 14, 90 upright side portions 27 which extend flatwise against the side portions 15, upwardly-converging portions 28 which conformingly fit against the lower portions of the converging walls 19 of the sill, a top portion 95 29 which extends substantially horizontal and fits against the bottom of the lower flange 30 of the I-beam 21, and a plate-portion 31 from which the various portions 26, 27, 28 and 29 extend at an angle and 100 with which they are preferably integrally formed.

The various cross-frame members referred to are of the same general construction, one of the intermediate cross-frame 105 members 12 being shown in detail and comprising plate-like portions 32 the inner ends of which, flanged at 33, conformingly fit against the sides of the center sill, as represented more particularly in Fig. 110 2, and to which they are riveted, as by the rivets represented at 34, 35 and 36, the rivets 34 extending through apertures 37 in the sides 27 of the spreaders, apertures 38 in the side portions 15 of the sills and 115 through apertures 39 in the flanges 33; the rivets 35 extending through apertures 40 in the side portions 27 of the spreaders, and openings in the side portions 15 of the sills and in the vertical flanges of the 120 bars 16, and through openings in the flanges 33; and the rivets 36 extending through openings in the horizontal flanges 18 of the bars 16, openings in the flanges 33, and also through a strap member hereinafter 125 referred to. The sections 32 are arranged in end to end alining relation, as shown, and extending from one to the other of these sections at their under sides and across the under sides of the center sill and the 130

spreader element, is the strap portion above referred to and represented at 41, this strap portion being riveted at its ends to flanges 42 provided on the lower edges of 5 the sections 32, as represented at 43. The strap portion 41 is also riveted to the horizontal flanges 18 of the bars 16 as by means of the rivets 36 extending through the flanges 42 and 18 and the strap member 41, and 10 is riveted to the lower member 26 of the spreader element as by the rivets indicated at 45. The spreader elements are also rigidly connected at their portions 29 with the lower flange 30 of the beam 21, as by 15 rivets 46 passing through these parts.

Each cross-frame member referred to is also formed with a plate-section 47 which extends from one side bar 13 to the other thereof, overlapping the horizontal flanges 20 48 of the latter to which they are secured as by rivets 49 which pass through these parts and flanges 50 provided on the upper edges of the sections 32, the member 47 being riveted at other places, at intervals, 25 to the flange 50, as represented at 51.

The movable plates hereinbefore referred to and forming the bottom of the car are represented at 52, two only of these plates being shown, these plates being hinged 30 connected with the center sill to extend at opposite sides thereof as shown in Fig. 3, as through the medium of the brackets 53 riveted, as indicated at 54, to the portions 19 and 20 of the center sill and carrying 35 pivot pins 55 which engage depending flanges 56 on the door sections 52, the arrangement of the doors and the hinging means referred to being such, as shown, that when the doors are in substantially horizontal position, as represented in Fig. 3, 40 they will form with the upper flange 24 of the beam 21 and the plate portions 47, a continuous bottom for the car, and are capable of swinging to outwardly and down- 45 wardly-inclined position to dump the contents of the car at the sides of the latter, the way in which these doors are releasably held in horizontal position and released to effect dumping not being shown as such 50 are well known in the art and form no part of the present invention.

It will be understood that by providing the I-beams in the upper zone of the center sill, this zone may be caused to present the 55 necessary amount of metal to render the tensile and compression zones of the sill substantially equalized, with the neutral axis of the sill extending substantially midway between the top and bottom surfaces of the 60 sill. This result may be accomplished regardless of the depth of sill rendered necessary for any particular construction of car, by the utilization of standard I-beams, which constructed in widely varying 65 portions including a wide variation in depth

of web portions, whereby it is not necessary to especially roll these reenforcing members.

Furthermore, the provision of the spreader elements 25 connected with the other parts 70 of the center sill is of advantage as they greatly strengthen the walls 19 of the sill, the lower flange 30 of the beam 21 affording a very desirable place of attachment for the spreader elements enhancing the stiffening function as well as aiding in the resisting of compression and tensile stresses in the upper zone of the sill, it being readily understood that the spreader elements operate to transfer the load imposed thereon to 75 the vertical side portions 15 of the sill.

It will also be observed that by arranging the various parts of the frame as shown and described, the frame including the center sill is rendered highly resistant to the 85 many stresses to which it is subjected in use.

While I have illustrated and described a particular construction involving my invention, I do not wish to be understood as intending to limit it thereto as the same may be variously modified and altered without departing from the spirit of my invention.

What I claim as new and desire to secure by Letters Patent is:

1. A center sill for a car extending substantially the full length of the car and formed with side walls at its upper portion spaced apart a less distance than the width of the sill at its lower portion, and a beam 100 having upper and lower flanges extending longitudinally of the sill substantially the full length of the car and interposed at its web portion between the upper portions of said side walls and secured to said side walls. 105

2. A center sill for a car extending substantially the full length of the car and formed with side walls at its upper portion spaced apart a less distance than the width of said sill at its lower portion, and an I-beam 110 having upper and lower flanges, extending longitudinally of the sill substantially the full length of the car and interposed at its web portion between the upper portions of said side walls and secured to 115 said side walls.

3. A center sill for a car extending substantially the full length of the car and formed of side walls spaced apart, the upper portions of said walls being spaced apart 120 a less distance than the lower portions thereof, and a beam having upper and lower flanges extending longitudinally of the sill and interposed at its web portion between the upper portions of said side walls and secured to said side walls, with its lower flange located between said side walls. 125

4. A center sill for a car extending substantially the full length of the car and formed of side walls spaced apart, the upper 130

- portions of said walls being spaced apart a less distance than the lower portions thereof, and an I-beam having upper and lower flanges extending longitudinally of the sill 5 and interposed at its web portion between the upper portions of said side walls and secured to said side walls, with its lower flange located between said side walls.
5. A center sill for a car extending substantially the full length of the car and formed with side walls converging upwardly towards the center line of the sill, and a beam extending substantially the full length of the car and having upper and lower flanges extending longitudinally of the sill 15 and interposed at its web portion between the upper portions of said side walls and secured to said side walls.
6. A center sill for a car formed as a hollow structure comprising side walls which are spaced apart at the upper portion of the sill a less distance than the width of said sill at its lower portion, a reinforcing bar extending lengthwise of said sill at the upper portion of the latter, and a series of spreader-elements located between said side walls and directly connected with said bar.
7. A center sill for a car formed as a hollow structure comprising side walls which are spaced apart at the upper portion of the sill a less distance than the width of said sill at its lower portion, a reinforcing bar having upper and lower flanges, said bar extending lengthwise of said sill and located at the upper portion thereof and a series of spreader-elements located between said side walls, said spreader-elements being connected with said side walls and with the lower flange of said bar.
8. A center sill for a car formed as a hollow structure comprising side walls which are spaced apart at the upper portion of the sill, a less distance than the width of said sill at its lower portion, a reinforcing I-beam interposed at its web portion between said side walls at the upper portion of the sill

and secured to said side walls, and a series of spreader-elements located between said side walls and connected therewith and with the lower flange of said I-beam.

9. An underframe for a car formed of a center sill structure and cross frame members extending crosswise of said sill, means connecting said cross frame members to said sill, said sill being formed with side walls and a reinforcing bar extending lengthwise thereof and connected therewith along the upper portion of the sill, and spreader-elements located between said side walls and connected with the lower flange of said bar.

10. In a car underframe, the combination of a center sill structure and cross frame members connected therewith at intervals, said center sill structure comprising side walls converging upwardly at their upper portions and terminating in substantially vertical portions, an I-beam extending lengthwise of the sill and interposed at its web portion between the upper extremities of said side walls and connected with the latter, and spreader-elements located between said side walls and conformingly fitting interior surfaces thereof and connected at their upper portions with the lower flange of said I-beam in flatwise opposed relation thereto, said crossframe members being each formed in sections located at the opposite sides of said sill and secured at their inner ends to said sill.

11. A center sill for a car formed as a hollow structure comprising side walls which are spaced apart at the upper portion of the sill a less distance than the width of sill at its lower portion, a reenforcing I-beam interposed at its web portion between said side walls at the upper portion of the sill and secured to said side walls, and a series of diaphragm spreader elements located between said side walls and connected therewith and with the lower flange of said I-beam.

ROBERT R. WEAVER.
